AXEL BREMBERG, OF GLASGOW, SCOTLAND.

BREECH MECHANISM FOR ORDNANCE.

1,318,840.

Specification of Letters Patent. Patented Oct. 14, 1919.

Application filed February 26, 1919. Serial No. 279,389.

To all whom it may concern:

Be it known that I, AXEL BREMBERG, a subject of the King of Great Britain and Ireland, and a resident of Glasgow, Scotland, have invented certain new and useful Improvements in Connection with Breech Mechanism for Ordnance, and of which the following is the specification.

The invention relates to breech-mechanism of that type in which the breech-plug is mounted upon a pintle screwed to the same pitch as that of the breech and carried on a carrier swinging on a vertical pivot on the gun breech, and in which the opening and closing of the breech by the breech-plug is effected by the combination of a member operated either directly by hand or through gearing or power, and turning in a plane at right angles to the axis of the breech face, a link, and articulative means connecting the ends of the link respectively to the breech-plug and to the operating member; and the invention has for its object to improve the construction and action of such mechanism and provide a simple, effective and inexpensive form of spherical joints as the articulative means connecting the link with both the breech block and the operating member.

An example of the improved mechanism is shown on three accompanying sheets of explanatory drawings, Figure 1, Sheet 1, being an elevation of the breech end of a gun and Fig. 2, Sheet 2, a plan of same, showing the improved mechanism, Figs. 3 and 4, Sheet 3, are elevations at right angles to each other of the connecting link. Fig. 5 is a section on the line *a—a* Fig. 1, and Fig. 6 a section on the line *b—b* Fig. 1 showing the improved form of spherical joint, these two figures being to an enlarged scale.

As shown in the drawings, the breech-plug A is mounted as usual on a pintle A¹ on a carrier A² swinging on a vertical pivot A³ at one side of the breech of the gun. To rotate the breech-plug A in order to engage and disengage its interrupted screw threads from the interrupted threads of the breech and to swing the carrier A² carrying the breech-plug into the open and closed positions, there is provided a usual operating hand lever B formed in a piece with or mounted on a vertical pivot B¹ turning in bearings in the carrier A². According to the invention, this lever B has on it a pin B² the axis of which is vertical. On this

pin is the sphere member B³ of a spherical joint, the sphere member being constructed and held on the pin B², as hereinafter described. The hollow spherical member C of this joint is formed in one end of a link C¹, the other end of which has formed on it a like hollow spherical member C² engaging a second sphere member C³, similar to the sphere member B³. This sphere member C³ is on a pin D mounted on the breech-plug A, the axis of this pin D being horizontal and at right angles to the axis of the pin B² on the hand lever B.

In order that the hollow spherical joint members C, C² on the link C¹ may be in one piece, the sphere members B³, C³ on the pins B², D are not complete spheres but are equatorial sections of spheres of such width that they may be passed through a slot D¹ formed in one side of each hollow spherical member C, C², afterward being turned around to receive the pins B², D. After the sphere members B³, C³ have been placed on the pins B², D, they are held in place by washers D² secured by screwed bolts D³ passed into recesses screwed to receive them in the outer ends of the pins, the outer surface of these washers being curved to the same radius as that of the periphery of the sectional spheres B³, C³, these sectional spheres and washers together making a sufficiently complete sphere to permit of ample relative movement of the parts, while the construction is inexpensive and at the same time substantial.

The movement of the hand lever B away from and toward the breech acts through the link C¹ in known manner to open and close the breech-plug A as hereinbefore described, and it will be seen that the relative points of pivoting of the link upon the breech-plug and upon the hand lever are so devised that the link passes beyond dead center when the breech-block is completely locked in the breech. Thus, if any force other than that due to proper actuation of the device tends to unscrew the breech-plug, it causes the link to retain the lever in the closed position.

What I claim is:

1. Breech-mechanism of the type described for ordnance, comprising in combination an operating member turning in a plane at right angles to the breech of the gun, a link, and spherical joints connecting the ends of the link respectively to the breech-plug and

to the operating member, each spherical joint comprising a hollow spherical member in one piece having a slot in one side thereof, a sphere member of an equatorial section of 5 a sphere of such width that it may be entered through the slot and turned around within the hollow spherical member, a pin entered into the sectional sphere member, and means to hold the pin and sectional 10 sphere together.

2. Breech-mechanism of the type described for ordnance, comprising in combination an operating member turning in a plane at right angles to the breech of the gun, a link, 15 and spherical joints connecting the ends of the link respectively to the breech-plug and

to the operating member, each spherical joint comprising a hollow spherical member in one piece having a slot in one side thereof, a sphere member of an equatorial section of 20 a sphere of such width that it may be entered through the slot and turned around within the hollow spherical member, a pin entered into the sectional sphere member, and means to hold the pin and sectional 25 sphere together, said means comprising a bolt and washer, the washer being shaped to partially complete the sectional sphere, substantially as described.

In testimony where I have signed my 30 name to this specification.

AXEL BREMBERG.
